United States Patent Office

Des. 177,039
Patented Mar. 6, 1956

177,039

DRESS

Evelyn Gold, New York, N. Y.

Application August 19, 1955, Serial No. 37,576

Term of patent 3½ years

(Cl. D3—26)

Fig. 1.

Fig. 2.

I claim:

The ornamental design for a dress, substantially as shown.
